UNITED STATES PATENT OFFICE.

JAMES W. CARPENTER, OF BROOKLYN, NEW YORK.

LOCKING MECHANISM FOR VAULTS.

1,137,739.

Specification of Letters Patent.

Patented May 4, 1915.

Application filed December 2, 1909. Serial No. 530,822.

To all whom it may concern:

Be it known that I, JAMES W. CARPENTER, of Brooklyn, in the county of Kings, and in the State of New York, have invented a certain new and useful Improvement in Locking Mechanism for Vaults, and do hereby declare that the following is a full, clear, and exact description thereof.

The object of my invention is to provide a locking mechanism for vaults, which has exceptional strength, which is positive in operation, which may be readily operated, and which is provided with power connections for effectively locking and unlocking the same.

A further object of my invention is to provide an adjustable grill which may be moved into and out of position in front of the door opening by any one upon the interior of the vault, and which may also be operated by anyone outside of the vault, who is familiar with the combination of the lock used upon the vault.

I have shown one embodiment of my invention in the accompanying drawings, in which—

Figure 1 is an elevation of a vault equipped with a door adapted to be locked by means of my improved form of locking mechanism; Fig. 2 is a horizontal cross-section of the same, showing the door in its open position; Fig. 3 is a transverse cross-section of the portion of the wall which is provided with the combination lock and valve-operating mechanism; Fig. 4 is a transverse vertical cross-section taken at right angles to the section shown in Fig. 3 upon the line 4—4 of said figure; Fig. 5 is a similar transverse cross-section taken on the line 5—5 of Fig. 3; and Fig. 6 is a diagrammatic representation of the entire operating system for the locking mechanism.

In the drawings, 1 is a vault which is provided with a door 2 supported upon a rotary bracket 3, pivoted upon a journal 4 of the usual type. The front of the door 2 is provided with a plurality of radiating rods 5 designed to be operated by means of a hand-wheel 6 to engage with recesses provided in brackets 7 carried by the door casting, in order to bring the door into its completely closed position. The door 2 is also provided with a handle 8 for opening and closing the same. Through the front of the wall 1 projects a shaft 9 carrying a hand-wheel 10 for operating the same. The shaft

9 carries upon its inner end adjacent to the inner surface of the wall of the vault a valve 11, having curved passages 12 and 13, designed to register with passages 14 and 15 provided in a removable block 16 inserted in the inner face of the wall of the vault. The block 16 is retained in position in the face of the vault wall, and in its proper position in relation to the valve 11, by means of a nut 17, which engages a screw-threaded shank 18 attached to the center of said valve 11. In front of the valve 11 the wall of the vault is provided with a circular cavity 19, the inner wall of which is provided with a pair of electrical contacts 20 and 21. A rotary circuit breaker 22 is carried by the shaft 9 opposite these contacts 20 and 21, so that in a certain position of the shaft 9 the circuit is completed from one of the contacts 20 through the circuit breaker 22 to the other of said contacts. Immediately in front of the circuit breaker 22, the shaft 9 also carries a slotted projection 23 with which a bolt 24 co-operates. The position of the bolt 24 is controlled by means of a tumbler mechanism 25, which is operated as in the case of all combination locks, by a hand-wheel 26, the hand-wheel in this instance being carried upon a sleeve 27 which surrounds the shaft 9.

The valve 11 containing the ports 12 and 13, is designed to control the admission of compressed air from an air compressor 28 to a pair of cylinders 29 and 30. In one position of the valve 11, as shown in Fig. 6, the air is conveyed from the air compressor 28 through a pipe 31 to the valve 11, whence it passes into a pipe 32, having one branch 33 leading to the inner end of the cylinder 29, and another branch 34 leading to the corresponding end of the other cylinder 30. While the valve 11 is in this position, the other passage 13 therein permits the air to be exhausted from the other ends of the cylinders 29 and 30. This is effected by means of a pipe 35 leading from the outer end of the cylinder 29, which pipe is connected with a similar pipe 36 leading from the corresponding end of the cylinder 30, which pipes are connected through the passage 13 in the valve 11 to an exhaust pipe 37. By merely changing the position of the valve 11, it will be seen that the compressed air can be led into the outer ends of the cylinders, instead of to the inner ends, as shown in Fig. 6, and that when the air is thus led

to the outer ends of the cylinders 29 and 30 the air is simultaneously exhausted from the inner ends thereof. In either of these positions an electric circuit is completed through the electrical contact 20 and 21, and current is caused to pass from a source of electrical energy 38 through leads 39 and 40 to an electric motor 41, which is geared by means of gearing 42 to the air compressor 28. When the valve 11 is thus moved into a position in which it permits air to enter the cylinders 29 and 30, the electrical circuit is completed through the electric motor 41, thereby driving the air compressor 28. Provision is made for a local supply of electrical energy, in case the main source of electrical energy 38 fails, and for this purpose I provide a storage battery 43, which is connected by means of wires 44 and 45, the latter containing a hand-operated switch 46, to the leads 39 and 40 respectively.

The air which is admitted to the cylinders 29 and 30 is designed to move pistons 47 and 48 therein, which pistons are connected by piston rods 49 and 50 to a pair of semi-circular locking blocks 51 and 52. The locking blocks 51 and 52 carry a plurality of flanges 53, which are designed to engage with corresponding recesses 54 provided upon the periphery of the vault door. Each of the locking blocks 51 and 52 also carries a semi-circular grill 55, the purpose of which is to temporarily close the vault door opening when the door 2 is opened.

I also provide means for operating the pistons 47 and 48 from the interior of the vault, and for this purpose I provide a valve 56, which is designed to be operated by a hand-wheel 57. The valve 56 carries a pair of passages 57^a and 58, similar in character to the passages 12 and 13 in the valve 11. The passages 57^a and 58 are designed to open and close connection from the air compressor 28 to the two ends of the cylinders 29 and 30, in a similar manner to that already described in connection with the valve 11; and for this purpose a branch pipe 59 is provided, which leads from the pipe 31, connected to the air compressor 28, through the valve 56, and as shown in position of the parts in Fig. 6, to a pipe 60, which connects with the pipe 34, and thus to the two inner ends of the cylinders 29 and 30. Another pipe 61 leads from the pipe 36 to the valve 56, and as shown in Fig. 6, to an exhaust pipe 62. In this position of the parts the air is being exhausted from the two outer ends of the cylinders 29 and 30, and compressed air is being supplied to the other ends thereof. In the other position of the valve 56, the reverse operation will take place. Hand-wheels 62^a and 63 are provided in the pipes 31 and 59 respectively, so that while the valve 11 is in a condition to be operated, the air supply may be cut off

from the valve 56, and while the valve 56 is in a position to be operated, the air may be cut off from the valve 11. Upon the same shaft which carries the valve 56, a rotary circuit breaker 64 is provided, which is designed to complete the circuit between a pair of electrical contacts 65 and 66, which contacts are connected by means of wires 67 and 68 respectively to the circuit, which includes the electric motor 41 for operating the air compressor 28.

In the operation of the apparatus, assuming that the door 2 is closed, and that it is desired to open the door, the hand-wheel 6 is operated to withdraw the rods 5 from engagement with the blocks 7. The hand-wheel 26 is then operated to move the tumblers 25 into a position in which the bolt 24 is removed from engagement with the slotted block 23. The valve 11 can now be operated by turning the hand-wheel 10, so as to admit air to the inner ends of the cylinders 29 and 30, the valve being moved into the position shown in Fig. 6 for this purpose. While the valve 11 is being operated in this manner, the hand-operated valve 63 is, of course, in its closed position. As air is admitted to the inner ends of the cylinders 29 and 30 from the air compressor 28, which is being operated by the electric motor 41 owing to the completion of the electric circuit through the circuit breaker 22, the locking blocks 51 and 52 are drawn outwardly until the flanges 53 thereon are disengaged from the recesses 54 upon the door 2.

When said disengagement is complete, the door can be opened by pulling on the handle 8 attached thereto. The hand-wheel 10 will now be turned slightly so as to disconnect the passages 12 and 13 in the valve 11 from the passages 14 and 15, and so as to break the electric circuit through the motor 41. The vault is now accessible from the exterior. Should any one now enter the vault and desire to close the grill 55 while upon the interior of the vault, the same can be accomplished by closing the hand-operated valve 62^a, opening the hand-operated valve 63, and rotating the valve 56 until the passages 57^a and 58 therein cause the air to be exhausted from the inner ends of the cylinders 28 and 29, and compressed air supplied to the other ends thereof. When the grill has thus been closed the valve 56 is moved into a position in which the passages 57^a and 58 are moved out of registry with the connecting pipes, and the circuit, including the circuit breaker 64, has been broken. The grill 55 is opened when desired by the reverse series of operations. The grill 55 may be also opened and closed from the exterior of the vault, if desired, by properly operating the hand-wheel 10 connected to the valve 11. In case the electrical energy from the main source of supply 38 fails, the storage battery 43,

which has been previously charged with electricity, may be thrown into the circuit by moving the switch 46. It is to be understood, however, that the switch 46 is normally open.

While I have described my invention above in detail, I wish it to be understood that many changes may be made therein without departing from the spirit of my invention.

I claim:

1. In a device of the character described, a wall, a door, a locking mechanism carried by the wall, means for operating said locking mechanism, and a grill attached to said locking mechanism.

2. In a device of the character described, a wall, a door locking mechanism coöperating therewith, a manually-operated combination lock for controlling the same, and connections providing compressed air for operating said locking mechanism.

3. In a device of the character described, a wall, a door, locking mechanism therefor, a retainer providing compressed air for operating said locking mechanism, including a hand-operated valve and a lock for controlling the locking mechanism and adapted to control said valve.

4. In a device of the character described, a wall, a door, locking mechanism therefor, a retainer providing compressed air for operating said locking mechanism, a lock for controlling the locking mechanism, and an electrically operated air compressor also controlled by said lock for supplying the compressed air retainer with air.

5. In a device of the character described, a wall, a door, locking mechanism therefor, a retainer providing compressed air and devices for operating said locking mechanism operable from both sides of the wall.

6. In a device of the character described, a wall, a door, locking mechanism therefor, a retainer providing compressed air for operating said locking mechanism, an air compressor for replenishing the supply of compressed air and a controlling device for controlling the supply of compressed air to the retainer and for operating the air compressor while the locking mechanism is being operated.

In testimony that I claim the foregoing I have hereunto set my hand.

JAMES W. CARPENTER.
